(57) **CLAIM**

I claim the ornamental design for flying pet toy, as shown and described.

DESCRIPTION

FIG. 1 is a front perspective view illustrating the design of the flying pet toy of the present invention;

FIG. 2 is a top plan view thereof;

FIG. 3 is a bottom plan view thereof;

FIG. 4 is a right side view, the left side view being essentially a mirror image thereof; and,

FIG. 5 is a back view thereof.
